CLAIM

The ornamental design for a wind guard for a griddle grill as shown and described.

DESCRIPTION

FIG. 1 is a front, right and top perspective view of a wind guard for a griddle grill, showing my new design;

FIG. 2 is a rear, left and top perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is rear, right and top perspective view thereof, showing in closed condition.

The broken lines illustrate portions of the wind guard for a griddle grill, that form no part of the claimed design.
